UNITED STATES PATENT OFFICE.

JOHN YANIK, OF COPLAY, PENNSYLVANIA.

ICE-CREEPER.

1,349,542.

Specification of Letters Patent. Patented Aug. 10, 1920.

Application filed March 1, 1920. Serial No. 362,511.

To all whom it may concern:

Be it known that I, JOHN YANIK, a citizen of Poland, residing at Coplay, in the county of Lehigh and State of Pennsylvania, have invented certain new and useful Improvements in Ice-Creepers, of which the following is a specification.

This invention relates to certain new and useful improvements in ice creepers particularly adapted for quick attachment to or detachment from the heel of a boot or shoe.

The primary object of the present invention is to provide an extremely durable and efficient ice creeper of this kind which may be cheaply and easily manufactured and which includes such construction of parts as to be easily placed in use and retained upon a heel without liability of accidental displacement therefrom.

Other objects will appear as the nature of the invention is better understood, and the same consists in the novel form, combination and arrangement of parts hereinafter more fully described, shown in the accompanying drawing and claimed.

In the drawing wherein like reference characters designate corresponding parts throughout the several views,

Figure 1 is a top plan view of an ice creeper attachment constructed in accordance with the present invention with its parts in fastening or clamped arrangement.

Fig. 2 is a front elevational view thereof,

Fig. 3 is a side elevational view of the same,

Fig. 4 is a transverse sectional view thereof taken substantially upon line IV—IV of Fig. 1, and

Fig. 5 is a view similar to Fig. 1 with the parts of the creeper in expanded or unfastened position.

Referring more in detail to the several views, the present invention embodies a pair of plates 5 and 6 adapted to be positioned against the under surface of a shoe heel at the opposite sides of the latter and respectively provided with marginal flanges 7 and 8 adapted to snugly embrace the periphery of the heel when the device is operatively disposed on said heel. The plates 5 and 6 are provided with suitable calks 9 of any desired kind adapted to penetrate ice or the like so as to prevent slipping in the usual manner, and, as shown, these calks are of the well known detachable screw threaded type. The flanges 7 and 8 of the plates 5 and 6

are curved in conformity to the shape of a shoe heel and are hingedly connected as at 10 at their rear ends so that the plates 5 and 6 may be swung toward or away from each other for facilitating the attachment to and detachment from the heel. The plates 5 and 6 are normally held in an expanded position wherein the flanges 7 and 8 are spaced farther apart than the width of the shoe heel by means of springs 11 which are herein shown of flat sheet metal form, one of the same being rigidly fastened at one end to the flange 7 as at 12 and having its free end bearing upon the other flange 8, while two of said springs are similarly rigidly fastened as at 13 to the flange 8 and have their free ends bearing upon the flange 7 of the plate 5. As the springs 11 are formed of strips of springy metal normally tending to assume the shape shown in Fig. 5, it will be seen that said springs will serve to separate the plates 5 and 6 as shown in Fig. 5. It is to be understood that the springs 11 may be used in any desired number and that the same are fastened to the flanges 7 and 8 adjacent the pivotal connection 10.

The flanges 7 and 8 are angularly directed toward each other at their ends as at 14 and 15 so as to lie substantially in contact with the breast portion of the shoe heel, and said angular ends of the flanges are short so as to be at all times spaced some distance apart as clearly shown in Figs. 1, 2 and 5. A link 16 is hingedly fastened at one end to the flange 14 as at 17, and the other end of the link 16 has a tightening lever 18 hinged thereto. A keeper plate 19 is hinged as at 20 to the free end of the flange 15 in any suitable manner and is provided with an aperture or opening 21 through which the lever 18 is adapted to be directed so that when said lever is folded backwardly parallel with the links 16 as shown in Fig. 1, the plates 5 and 6 are drawn toward each other against the action of the springs 11 and the device is thereby freely clamped upon the heel and thus retained.

By reason of the link 16 and the hinging of the keeper plate 19, the device is made quite flexible at this point so that the device may be more readily manipulated.

From the foregoing description it is believed that the construction and operation of the present invention will be readily understood by those skilled in the art.

While the preferred embodiment of the

invention is shown, it is nevertheless to be understood that minor changes may be made without departing from the spirit and scope of the invention as claimed.

5 What I claim as new is:—

An ice creeper comprising a pair of flanged side plates having ground engaging calks and hingedly connected together at their rear ends, means to yieldingly nor-

mally separate said plates at their forward ends, and means at the forward ends of said plates to move the latter toward each other whereby the flanges of said plates are brought and retained firmly into engagement with the periphery of a shoe heel. 10

15 In testimony whereof I affix my signature.

JOHN YANIK.
